UNITED STATES PATENT OFFICE.

SAMUEL G. DORMAN, OF POPLAR BLUFF, MISSOURI, ASSIGNOR, BY MESNE ASSIGNMENTS, TO THE DALTON ADDING MACHINE COMPANY, OF CINCINNATI, OHIO, A CORPORATION OF OHIO.

ADDING AND RECORDING MACHINE.

1,166,116.

Specification of Letters Patent. Patented Dec. 28, 1915.

Application filed April 29, 1907. Serial No. 370,824.

To all whom it may concern:

Be it known that I, SAMUEL G. DORMAN, a citizen of the United States, residing at Poplar Bluff, Missouri, have invented a new and useful Adding and Recording Machine, of which the following is a specification.

This invention relates to adding and recording machines, and it consists of the novel construction, combination and arrangement of parts hereinafter shown, described and claimed.

This invention relates particularly to that class of adding and recording machines which utilize two or more type-carriers which are operable side by side for recording purposes, and in which two or more characters can be recorded at one operation. Heretofore these machines have been constructed in this manner, and provided with mechanism which is operated automatically to add all of the numbers recorded. Some machines have been provided with mechanism to eliminate or dissipate from the number in the adding mechanism the last number recorded, which operation is desirable in cases of error.

Occasions arise when it is desirable to record columns or lists of numbers, make and record a total of some of the numbers so recorded, and omit others from the total. These numbers should be recorded in consecutive order irrespective of whether they are to be added or not.

The object of the present invention is to produce a machine of the type referred to which shall contain mechanism operable or adjustable to permit subsequent operation of the recording instrumentalities to record numbers without causing the totalizing mechanism to operate to add such numbers.

A particular object of the invention is to produce a machine of the class referred to comprising mechanism operable to record numbers, mechanism operable automatically to add numbers recorded, and mechanism operable or adjustable effectively to prevent the addition of numbers by the adding mechanism when the recording mechanism is operated to record such numbers.

A further object is to produce a machine of the kind mentioned which is operable to record lists or columns of numbers, add cer-

tain of said numbers together during the recording operation and omit others of said numbers from the total as desired by the operator, and to produce a visible sign or character to indicate such of the recorded numbers as are not included in the total.

Another object is to produce a machine of the character described comprising mechanism operable to record numbers, mechanism operable automatically to add numbers recorded, and mechanism operable or adjustable effectively to prevent the addition of numbers by the adding mechanism when the recording mechanism is operated to record such numbers, in combination with mechanism operable to record words and other data in any desired relation to the recorded numbers.

A specific object is to provide the special mechanism for preventing operation of the totalizing mechanism during operation of the machine to record, in that type of machine shown and described in the application of Hubert Hopkins, for an adding and writing machine, filed January 24, 1903, Serial Number 140390, Patent No. 1,039,130; and in that machine shown and described in my former application for an adding and recording machine, filed October 16, 1906, Serial Number 339,230; and in that machine constituting the subject matter of Dorman and Clayton Patent No. 1,053,943 dated February 18, 1913, application for which was filed February 11, 1907.

In the drawings which form part of this specification I have illustrated the invention incorporated in and forming part of that particular machine shown and described in the said Dorman and Clayton Patent No. 1,053,943, though it will be obvious that the invention may readily be incorporated into machines of various other makes.

Other objects and advantages than those specifically named will be made obvious by the following description without particular mention.

Figure 1 is a longitudinal vertical sectional view of a machine, such as that illustrated in the Dorman and Clayton Patent No. 1,053,943, with the special devices for controlling the operation of the totalizing mechanism as required to permit operation of the machine to record numbers and cause

95

100

105

or prevent addition thereof as desired. Fig. 2 is a specimen of the work performed by this machine, showing one of the numbers in a column, which is omitted or "eliminated" from the total at the foot of the column, said omitted or "eliminated" number being designated by a special character opposite therefrom. Fig. 3 is a detail view, showing the base in section, and illustrating the train of mechanism whose operation permits subsequent operation of the machine to record numbers without adding such numbers. Fig. 4 is a perspective view of lock-controlling devices which coöperate with the recording mechanism to prevent locking of the "eliminating" train of mechanism prior to the commencement of the recording operation. Fig. 5 is a perspective view of the locking device whereby the "eliminating" train is locked to prevent operation thereof after commencement of any recording operation, so that it is impossible to prevent any number that is being recorded from being added or registered in the totalizing mechanism except in cases when the said "eliminating" train is operated or adjusted before the recording instrumentalities start toward recording position. Fig. 6 is a perspective view of the key for the "eliminating" train and the totals recording key, and also a locking device operated by each of said keys, whereby, when one of said keys is operated, the other one of said keys is locked against operation. Fig. 7 is a longitudinal sectional view of the drivers or hammer section of the machine and a portion of the key-board, illustrating the entire train of mechanism whose operation or adjustment prevents addition of any number or numbers recorded. Fig. 8 is a perspective view of the devices which cause a distinguishing character to be printed opposite from the recorded numbers that are not included in the total. Fig. 9 is a perspective view of the devices whereby the totalizing mechanism is rendered inoperative or idle when the "eliminating" mechanism is operated or adjusted. Fig. 10 is a cross sectional view of the machine just above the key board and the transversely movable pin carriage.

The entire machine is supported upon the base 1, the recording and operating mechanisms being upheld by suitable frames 2. A platen 3 is supported in a carriage 4 which is arranged to travel laterally on a carriage support or track 5, thereby affording means for moving the platen laterally for word, letter, and column spacing, and other purposes involved in the operation of the most efficient machines of this class. A series of typewriting type-bars 6 are disposed in position to strike the front of the platen to record words and other data, causing impressions on the paper through the medium

of a ribbon 7 which winds on spools at the sides of the machine. The type-bars are operated by trains of connections connecting them with their respective keys 8 which are arranged in rows on the key-board at the front of the machine. Suitable mechanism is provided in connection with the platen for rotating the same as required to effect movement of the paper for line spacing. The construction and arrangement of these various parts and the method of their operation are all fully disclosed in the said Dorman and Clayton Patent No. 1,053,943 and also in the British Patent No. 854, of 1904, before mentioned, and, therefore, do not require specific or detailed illustration or description in this specification.

The adding mechanism and the recording instrumentalities thereof are operably located within the same machine with the typewriting mechanism just above briefly described. A number of type-carriers 9 are operably supported between the frames 2 and on their front ends a series of types 10 are movably supported. There are ten of these types upon each type-carrier ranging consecutively from a type representing "0" at the extreme front to "9" at the rear. These type-carriers operate forward and backward in their recording movements. After the proper number has been struck on the key 11 and thereby set up in the transversely movable carriage 12 (Fig. 10), the main shaft 13 is rotated forwardly and, through the medium of a connecting link 14, releases the number of type-carriers required to record the number which had been set up and permits them to be actuated forwardly until they are stopped in position to record the number. When so positioned the required types are in alinement in front of the platen in position to be driven to record. When the actuating force is removed from the shaft 13 said shaft is drawn backward and the type-carriers are moved to idle position by springs 15. The carriage 12 is of that type which moves one space cross-wise of the machine at each operation of one of the keys 11, and carries a series of movable parts 11a which are pushed up by the keys to represent numbers. The step by step movement of the carriage may be controlled in any known manner, one way being by use of an escapement. This operation and arrangement of the carriage are described in the Hopkins patent aforesaid, and said parts are used in the machine and known commercially. The specific construction and arrangement of these parts are immaterial in so far as my present invention is concerned, and in practice I have adapted my invention to the machine in which said parts are used substantially as described in the Hopkins patent. A set of gear parts 16 are movable with the

type-carriers. A group of totalizing wheels 17 (Fig. 1) are mounted on a shaft 18 which is mounted in oblique slots in arms 19 attached to a rock shaft 20, so that by oscillating said arms forward and backward, the wheels will be raised and lowered; alternately, into and out of mesh with the gear parts 16. The link 21 is connected to one of the arms 19 and projects forwardly 10 adjacent to a lever 22 which is attached to the end of a rock shaft 23. Said lever 22 has a projection 24 near each end, one being above the upper edge of the link 21 and one extending under the lower edge of said link. 15 Notches 25 are formed in the edges of said link 21, and it is arranged so that when the machine is idle the projection 24 at the upper end of the lever 22 rests within the notch 25 in the upper edge of the link. 20 Rocking of the shaft 23 to swing the upper end of the lever 22 backward causes the link 21 to be pushed backward. This results in swinging the arms 19 backward and draws the wheels 17 downward out of mesh with the gear parts 16. It is arranged that these 25 parts shall operate automatically upon operation of the main shaft 13, all of which is fully described and illustrated in the Hopkins Patent No. 1,039,130 referred to. The 30 arrangement is such that the wheels 17 are lowered in this manner at the start of the shaft 13 and before the gear parts 16 start forward when any number is being recorded and are raised into mesh with the gear 35 parts the moment the shaft 13 starts on its return and just before the gear parts start backward. Thus the numbers recorded are introduced into and added within the wheels 17. Operation of the shaft 23 to effect 40 meshing and unmeshing of the wheels 17 and gear parts 16 by elevation and lowering of the wheels is accomplished by a cam 26 attached to the shaft 13 rubbing against a lever 27 on the shaft 23. The lever 27 is 45 loose on the shaft 23 and has a pin 28 projecting between the arms of a bifurcated member 29 which is rigid with the shaft 23, thereby allowing the lever 27 certain free movement without effecting the shaft. The 50 shaft 23 and the parts carried thereby are drawn and held in proper position when idle by a centering device 30 of known construction.

When the shaft 13 is started to record a 55 number the cam 26 (Fig. 7) rubs the lower end of the lever 27 and thereby rocks the shaft 23 which, as described, causes the lever 22 thereon to push the link 21 rearward to lower the wheels 17. The rear edge of the 60 cam 26 is eventually carried beyond the lever 27 and this occurs, as fully described in Patent 1,053,943 aforesaid, just about the time the types are driven to record, which is after the gear parts 16 have stopped. 65 Then when the parts are started on their

return by the springs 15 the cam 26 rocks the shaft 23 in the opposite direction which raises the wheels 17 into mesh with the gear parts 16 and causes the number that had been recorded to be added in the wheels. 70 It is obvious, therefore, that, if the lower end of the lever 27 be swung forward beyond possible contact with the cam 26 so as to lower the wheels 17 out of mesh with the gear parts 16, and so that the cam on 75 backward movement will not rub against said lever to raise the wheels, said wheels will remain lowered out of mesh with the gear parts, and the gear parts will return to idle position without causing that number 80 which had been recorded to be introduced or added in the wheels. The mechanism for preventing this articulation of the adding mechanism and recording mechanism to permit independent operation of the recording mechanism is the special subject-matter of this invention, but it is to be understood that such subject-matter comprises part of a complete adding and recording machine 85 which is operable to perform the functions of recording and adding numbers. The types are driven to record by a series of drivers or hammers 31 which are pivoted on a shaft 32 (Figs. 1 and 7). These hammers are arranged in a group, usually referred to as the "hammer section," and are held in idle position by a series of pawls 33, provided with hooks to engage with similar hooks on the hammers. To each pawl a trip-bar 34 is pivoted, said trip-bars extending rearward from the pawls through a slotted supporting member 35. Springs 36 are connected to said trip-bars in such manner as to draw them rearward to hold the pawls in engagement with the hammers. A 100 rod 37 limits rearward swing of the pawls when they are disengaged from the hammers. Two arms 38 on the shaft 32 carry a bar 39 extending crosswise under the rear extensions of the hammers and acting to restore the hammers to idle position, as shown in Fig. 7, when the shaft 32 is rocked to raise said bar. Automatic devices, which it is not necessary here to illustrate nor describe, act to rock the shaft 32 and lower the 105 bar 39 during forward movement of the type-carriers to record a number, and when the hammers are released from their pawls said hammers are thrown against the types by springs 40, thereby driving the types to 110 record. Each of the trip-bars 34 has a tongue or extension 41 extending under the one in the next lower order so that when any one of said trip-bars is raised it lifts up all others in the lower orders. When idle the rear ends of the trip-bars 34 are below the arc in which the bar 39 is carried so that said bar 39 will pass above all of the trip-bars except those whose ends have been 115 raised. Automatic means are utilized to 120

125

130

raise the rear ends of the trip-bars corresponding to the type-carriers which operate to record a number, and, after the type-carriers stop in recording position, the bar 39 strikes the rear ends of the trip-bars 34 which had been raised and pushes them forward thereby releasing the pawls 33 therefrom. Said hammers so released are thereupon thrown against the type 10 by the springs 40 and, after performing this function, are automatically reengaged with the pawls 33 by return of the bar 39. Only the hammers necessary to drive type to record the characters in the 15 number being recorded are released while all others in higher orders are held idle, the bar 39 passing over the bars 34.

The foregoing mechanisms are all included in the machine shown and described 20 in my said joint application and in the Hopkins British Patent No. 854, of 1904, and, for such reason, do not require extended illustration or description here, it being sufficient for present purposes to know that 25 the parts act to perform the functions attributed to them. Each number recorded is automatically taken up or added within the wheels 17, and heretofore there has been no provision in this class of machines whereby 30 a number could be recorded and kept out of or "eliminated" from the total. My invention, as an embodiment in and part of such machines, comprises mechanism to enable the operator to record numbers and 35 keep out or "eliminate" any desired ones thereof from the total. In addition it consists of means for indicating those numbers which are so "eliminated."

Having described the essential features of 40 one type of machine with which this mechanism is combinable, I will now describe the mechanism for performing the functions outlined. Within the key-board a special key 42 (Figs. 3, 7 and 10) is arranged, said 45 key having a stem which operates through a slot in the key-board plate 43 and through a slot in the base 1. A rock shaft 44 is supported in bearings 45 attached to the under side of the base and has an arm 46 extending 50 forwardly into a slot 47 in the lower end of the key-stem 42. A spring 48 is connected to an arm 49 on said shaft 44 and to the base of the machine, thereby holding the shaft in idle position, and upholding the 55 key 42. A rearwardly extending arm 50 on the shaft 44 is pivoted to the lower end of a link 51 whose upper end is connected to an arm 52 attached to and extending obliquely downward and rearward from a rock-shaft 60 53 mounted under the hammer section. An arm 54 on said rock shaft supports a depending link 55 provided with an elongated vertical slot 56. Said link extends alongside of the lever 27 and a pin 57 on said lever 65 extends through the slot 56, (Figs. 7, 8 and

9) and permits movement of the lever 27 by the cam 26 without disturbing the link 55 or the parts connected therewith. However, if the key 42 be depressed as far as it will go it causes the arm 54 to raise a sufficient distance to swing the lower end of the lever 27 forwardly beyond possible engagement with the cam 26 when it swings forward and backward while recording a number. This operation of the lever 27 rocks the shaft 23 and pushes the link 21 rearward, thereby lowering the wheels 17 out of mesh with the gear parts 16 just the same as when operated by the cam 26. By holding the key 42 downward the cam 26 can swing in both directions without contact with the lever 27, thereby permitting the type-carriers to travel in both directions and to record a number without operating the total wheels 17, said type-carriers and the other parts of 85 the recording mechanism operating freely to perform their functions, the numbers so recorded being excluded or eliminated from the total of other numbers that may be recorded and added. The numbers so recorded and eliminated from the total may, for purposes of identification, be designated by printing a suitable character opposite therefrom. A lever 58 (Fig. 7) is suspended in the hammer section and has a vertical arm 90 and a horizontal arm. The vertical arm extends behind a pin 59 on a lever 60 extending obliquely downward and rearward from the shaft 23, so that when the shaft 23 is rocked by depression of the key 42 the lever 100 58 will be oscillated. A plate 61 whose upper edge is even with the upper edges of the trip-bars 34 is pivoted at its front end to the trip-bar in the highest order, and its rear end is even with the rear ends of said trip-bars. The horizontal arm of the lever 58 is underneath the plate 61 and, when oscillated, raises the rear end of said plate into the path of travel of the bar 39, without, however, raising the end of the trip-bar 34. The bar 39 moving forward strikes the end of the plate 61 and releases the pawl 33 in the highest order, thereby permitting the hammer 31 in that order to be thrown by its 110 spring 40.

It will be remembered that, as fully described in my said joint application above identified, when any number is recorded all of the type-carriers move forward to present the foremost types thereon, representing "0", at the printing or recording line. It is obvious that there is no use for a "0" on the type-carrier in highest order, and that type may be displaced by a type of a suitable character to designate a number not included in the total. This, however, is not essential and the "0" may be retained if desired for it is not essential that any particular or specific character be used. In the present instance in the example illustrated 120 125 130

in Fig. 2 I have employed the letter "E". When the number that is to be recorded and omitted from the total has been set up in the machine, the key 42 is depressed and then 5 the type-carriers are moved toward recording position. Depression of the key 42 disconnects the total wheels from the gear parts 16 and raises the rear end of the plate 61. After the type-carriers have stopped side by 10 side in position to align the required types for recording the number, the necessary number of hammers are released, as described above, to drive the types to record. The hammer in the highest order will also 15 be released since the plate 61 is pushed forward by the bar 39. The foremost type on that type carrier will thereby be driven to record a character, in this instance on "E", opposite from the recorded number. Elevation 20 of the plate 61 does not disturb the trip-bars 34 in the lower orders since said plate is independently movable. By holding the key 42 down until the type-carriers return to idle position the number will have 25 been recorded without addition or registration thereof in the totalizer.

Means is provided to prevent depression of the key 42 after the machine has commenced an operation to record. A notch 62 30 is formed in the key stem 42. An angular locking member 63, (Fig. 5) comprising a vertical arm and a horizontal arm, is pivoted to a support 64, the horizontal arm of said member extending behind the key stem 35 42 (Fig. 7) in position to engage, when oscillated, in the notch 62 and thereby prevent depression of the key 42. The number 63 has an arm on its lower end and a spring 65 located below said arm to actuate the 40 locking member toward the key stem. A link 66 is pivoted to an arm 67 on the shaft 13 and is moved backward and forward during operations of the machine to record. The locking member 63 has a projection 68 45 which extends behind a lug 69 on the link 66 and thereby holds the locking member out of contact with the key stem 42. The moment the parts start to record the link 66 is pushed forward and releases the locking member 63 from restraint and permits 50 the spring 65 to engage said locking member in the notch 62. Backward movement of the link 66 moves the locking member out of the notch, so that the key 42 is oper- 55 able only before commencement of a recording operation. The key 42 is locked during the operation of recording a total. The totals recording key 70 is depressed whenever the total is to be recorded. The total 60 key 70 has connections 70^a leading to the link 21 whereby said key, when depressed, will lower the forward end of said link away from the upper projection 24, thereby permitting the shaft 23 to be rocked without moving the supports 17. In this way 65

the totalizing wheels will be retained in mesh with the gear parts or racks 16 during forward movement of the latter, thereby enabling the operator to print the total represented in said wheels in the usual and well 70 understood manner.

A plate 71 (Figs. 3, 6 and 7) is pivoted to the plate 43 between the key 42 and the totals recording key. Each of said keys has an inclined surface 72. When the totals 75 recording key is depressed the inclined surface 72 thereon rubs against the edge of the lever 71 and binds the other end of said lever against and under the inclined surface 72 on the key 42, thereby binding said 80 key 42 within the slot in the plate 43 in which it operates and locking said key against depression. This also prevents depression of the totals recording key when the key 42 is down, and holds both keys 85 against simultaneous depression.

A complete example of work performed by the recording mechanism of the adding department of this machine is illustrated in Fig. 2. A clear condition of the machine 90 having been indicated by depression of the totals recording key and operation of the shaft 13 (in any known manner) to release the type-carriers, and the consequent record of the character "0" at the head of the 95 column it is known that the machine is ready to commence work. A series of numbers are found to require record, some of which should be added and some (in this instance one) excluded or eliminated from 100 the total. The four first numbers are recorded and introduced or added in the wheels 17 as recorded, while the fifth number in the example shown is recorded, but is excluded or eliminated from the total 105 by the operation of the key 42. The distinguishing character "E" is recorded opposite from the eliminated number to indicate that it is not included in the total. Other numbers are then recorded and added 110 in with the number previously recorded and added and the final number recorded at two spaces below the one next above is the correct total of all the numbers above except that one which was omitted or eliminated. 115

It will be obvious that there may be many alterations and variations in the construction and arrangement of this invention, and it may be used in other embodiments without departing from the spirit and scope of the invention.

I do not restrict myself to the specific construction, arrangement or embodiment shown and described but

What I claim and desire to secure by Letters Patent is:

1. In an adding machine, type-carriers, hammers operable to drive the type on said type-carriers to print numbers, and auto- 130

- matic mechanism to add the numbers printed, in combination with mechanism whereby operation of said automatic adding mechanism may be prevented when said 5 type-carriers and hammers are operated and means controlled by said mechanism whereby one of the aforesaid hammers will be caused to operate, substantially as specified.
- 10 2. In an adding machine, type, a platen, spring impelled hammers operable to drive said type against said platen to record numbers, adding mechanism, a totals recording key, a separate key for preventing operation 15 of said adding mechanism when numbers are recorded by said type and hammers and devices controlled by said separate key whereby one of the aforesaid hammers will be caused to operate, substantially as specified.
- 20 3. In an adding machine, the combination of a spring-impelled hammer, a pawl for holding said hammer retracted, a trip bar for releasing said pawl from said hammer, 25 an actuator for actuating said trip bar to release said pawl, means normally holding said trip bar out of the path of movement of said actuator, means for moving said trip bar into the path of movement of said 30 actuator, and an element movable into the path of movement of said actuator independently of said trip bar.
- 35 4. In an adding machine, the combination with a series of spring-impelled hammers arranged in numerical orders, pawls holding said hammers retracted, tripping elements for releasing said pawls, an actuator for actuating said tripping elements to release said pawls from said hammers, means 40 normally holding said tripping elements out of the path of movement of said actuator, means for moving said tripping elements into the path of movement of said actuator so that said actuator will move 45 said tripping elements and release said pawls, means controlled by the tripping elements in higher orders for moving the tripping elements of lower orders into the path of movement of said actuator so that 50 all hammers toward lower orders will operate with the hammers operating in the highest order, and an optionally operable device for releasing the hammer in a higher order while the hammers in adjacent lower 55 orders remain held by said pawls.
- 60 5. In an adding machine, the combination with a hammer, a spring for actuating said hammer, means for moving said hammer in opposition to said spring to place said 65 spring under tension, an element holding said hammer in position to retain said spring under tension, a device for releasing said element to enable said spring to operate said hammer, and an actuator for moving said device to release said element, of

an additional device for releasing said element and movable into and out of the path of movement of said actuator, and optionally operable manual means for moving said additional device into the path of movement of said actuator whereby said element will be released from said hammer.

6. In an adding machine, the combination with a hammer, a spring for actuating said hammer, means for moving said hammer in opposition to said spring to place said spring under tension, a pawl arranged to engage and hold said hammer in position to retain said spring under tension, a type-carrier, an actuator, a device for releasing said element to enable said spring to operate said hammer, and means whereby said type-carrier will move said device into the path of movement of said actuator whereby said spring will be enabled to operate said hammer as an incident to the operation of said type-carrier, of an additional device movable into the path of movement of said actuator at the will of the operator whether or not said type-carrier is operated.

7. In an adding machine, a series of hammers arranged in numerical orders and movable to and from retracted positions, a latch member holding each hammer in its retracted position, a tripping element for each of said latch members, an actuator for actuating said tripping elements to release said latch members, means normally holding said tripping elements out of the path of movement of said actuator, and an additional optionally operable element movable into the path of movement of said actuator whereby one of said latch members may be optionally released.

8. In an adding machine, a series of hammers arranged in numerical orders and movable to and from retracted positions, a latch member for each of said hammers normally holding said hammers in their retracted positions, a movable actuator, a tripping element for each of said latch members movable into and out of the path of movement of said actuator, automatic means for moving said tripping elements into the path of movement of said actuator under predetermined conditions, and optionally operable manipulative means for effecting a release of one of said latch members by said actuator, substantially as described.

9. In an adding machine, the combination with a hammer movable to and from retracted position, a pawl normally holding said hammer in its retracted position, a movable actuator, a tripping element normally out of the path of movement of said actuator, and means for moving said tripping element into the path of movement of said actuator whereby said actuator will move said tripping element and re-

- lease said pawl from said hammer, of an independently movable device, and means for moving said device into the path of movement of said actuator to effect a release of said pawl.
10. In an adding machine, the combination with a series of hammers arranged in numerical orders and movable to and from retracted positions, pawls for holding said hammers in their retracted positions, tripping elements for releasing said pawls, a movable actuator for actuating said tripping elements to release said pawls, and means normally holding said tripping elements out of the path of movement of said actuator; of an additional element arranged to coöperate with said actuator to release one of said pawls, and manipulative means for moving said additional element independently of the corresponding tripping element to position to coöperate with said actuator.
11. In an adding machine, the combination with a type-driving hammer movable to and from retracted position, a pawl holding said hammer in retracted position, and a movable actuator, of an element movable into and out of the path of movement of said actuator, and manipulative means for moving said element into the path of movement of said actuator, whereby said element will be moved to release said pawl from said hammer.
12. In an adding machine, the combination with a spring-impelled hammer, a pawl holding said hammer in a retracted position, and a movable actuator, of an element for releasing said pawl from said hammer supported normally out of the path of travel of said actuator, and manual means for moving said element positively into the path of movement of said actuator, substantially as described.
13. In an adding machine, a series of hammers arranged in numerical orders and movable to and from retracted positions, a latch member holding each hammer in its retracted position, a movable actuator, a tripping element for each of said latch members normally out of the path of movement of said actuator, a device for moving each of said tripping elements into the path of movement of said actuator, means whereby the tripping elements in higher orders which move into the path of movement of said actuator will also move the tripping elements in lower orders into the path of movement of said actuator, whereby when any latch member in higher orders is released the remaining latch members in lower orders will also be released, an additional tripping element for one of said latch members, and means for moving said additional tripping element into the path of movement of said actuator independently of the corresponding first-named tripping element, whereby said latch member may be released independently of the adjacent latch members in lower orders.
14. In an adding machine, a hammer, a latch holding said hammer, a swinging bar, an element pivotally connected to said latch, means for moving said element to position to be engaged by said swinging bar to release said latch from said hammer, an additional element movable independently of said first-named element into the path of movement of said bar to release said latch, a lever for actuating said second-named element, and manipulative connections for operating said lever.
15. In an adding machine, a series of hammers arranged in numerical orders, a latch holding each of said hammers, a movable actuator, tripping elements movable into and out of the path of movement of said actuator and arranged to be moved thereby to release said latches, means whereby movement of the tripping elements in higher orders will move the tripping elements in the lower orders into the path of movement of said actuator to effect the release of the latches in lower orders from the tripping element in highest order which moves into the path of movement of said actuator, an additional tripping element for one of the latches in higher orders, and means for moving said additional tripping element into the path of movement of said actuator independently of the corresponding first-named tripping element, substantially as described.
16. In an adding machine, the combination with hammers to print numbers, and adding mechanism to add the numbers printed, of a key adjustable to prevent operation of said adding mechanism, and means for releasing one of the aforesaid hammers in addition to those required for printing a number when said key is adjusted as aforesaid, substantially as specified.
17. The combination with adding mechanism, and hammers for printing the numbers added, of mechanism adjustable effectively to prevent operation of said adding mechanism when numbers are printed, and means controlled by said mechanism for releasing one of said hammers, substantially as specified.
18. The combination with type-carriers, numeral type on said type-carriers, mechanism for operating said type-carriers effectively to position any desired type thereon in line for printing, a hammer for each of said type-carriers, and means for operating each of said hammers when the corresponding type-carrier is in any one of several positions, of adding mechanism operable to add the numbers printed, and a device for preventing said adding mecha-

- nism from operating and for causing one of the aforesaid hammers to operate, substantially as specified.
19. In an adding machine, the combination with a series of hammers arranged in numerical orders, pawls holding said hammers, a device for releasing said pawls, and couplings whereby the release of a pawl in a higher order will release the pawls in lower orders, of optionally operable means for releasing one of the pawls in a higher order without releasing pawls in lower orders controlled by said couplings.
20. In an adding and recording machine, hammers arranged in numerical orders, pawls holding said hammers, a device for releasing said pawls, couplings whereby release of a pawl in a higher order will release the pawls in lower orders, means for effecting release of a pawl in a higher order without releasing the adjacent pawls in lower orders, and a manually operable element controlling said means.
21. In an adding machine, hammers arranged in numerical orders, pawls holding said hammers, type-carriers arranged in numerical orders corresponding to said hammers, means controlled by said type carriers for releasing the corresponding hammers as an incident to the operation of said type-carriers to and from predetermined recording positions, and additional manipulative means controlling the release of certain of said hammers.
22. In an adding machine, hammers arranged in numerical orders, type-carriers arranged in numerical orders and movable to and from selected recording positions, automatic means for effecting operation of hammers corresponding to type-carriers operated to and from recording positions, and additional means controlling the operation of one of said hammers as an incident to the operation of any of said type-carriers.
23. In an adding machine, hammers arranged in numerical orders, type-carriers arranged in numerical orders and movable to and from selected recording positions, automatic means for effecting operation of hammers corresponding to type-carriers operated to and from recording positions as an incident to the operation of said type-carriers, and optionally operable means controlling the operation of one of said hammers as an incident to the operation of any of said type-carriers.
24. In an adding machine, type-carriers arranged in numerical orders and movable to and from selected recording positions, hammers arranged in numerical orders corresponding to said type-carriers, devices for holding said hammers, automatic means for releasing hammers corresponding to type-carriers operated to and from recording positions, an additional device for releasing one of said hammers, and optionally operable means controlling said additional device.
25. In an adding machine, type-carriers arranged in numerical orders and movable to and from selected recording positions, hammers arranged in numerical orders corresponding to said type-carriers, pawls holding said hammers, releasing devices for said hammers controlled by said type-carriers, and an additional optionally operable releasing device for one of said hammers.
26. The combination with a set of numeral type, mechanism operable to position said type side by side to represent numbers, hammers arranged to drive said type to print numbers, and adding mechanism operable to add the numbers printed, of mechanism for preventing operation of said adding mechanism when selected numbers are recorded, a type representing a character not a part of a number, and means whereby one of said hammers may be caused to strike certain of said numeral type in printing certain numbers, or said last-named type when certain numbers are printed which are not added upon said adding mechanism.
27. In an adding machine, the combination with adding wheels arranged in numerical orders, type-carriers arranged in numerical orders controlling said adding wheels, a series of numeral type on each of said type-carriers, a non-numeral type on one of said type-carriers, a hammer for driving the type on each of said type-carriers to record, and mechanism adjustable to enable said type-carriers to operate independently of said adding wheels to record selected numbers, of means for causing one of said hammers to drive said non-numeral type to record when a number is recorded and not added, substantially as described.
28. In an adding machine, a series of type-carriers, a plurality of numeral type on each of said type-carriers, an additional type-carrier, a plurality of numeral type on said additional type-carrier, a non-numeral type on said additional type-carrier, adding mechanism controlled by said first-named type-carriers and by said second-named type-carrier, optionally operable means for preventing operation of said adding mechanism when said first-named type-carriers operate to record numbers, and means for driving said non-numeral type on said additional type-carrier to record when said first-named type-carriers record a number which is not to be added, substantially as described.
29. In an adding machine, mechanism operable to record numbers, wheels operated incidentally to the recording operations to add the numbers recorded, a train of elements adjustable to prevent operation of said wheels when said numbers recording mechanism is operated, a hammer, a latch holding said

- hammer, a swinging bar, an element pivotally connected to said latch, and means operated by said train of elements to move said pivoted element in the path of movement of 5 said swinging bar, substantially as specified.
30. The combination with adding wheels, trains of recording devices arranged in numerical orders, means for operating said trains of recording devices to record numbers, means for operating said adding wheels when said recording devices are operated, a train of connections enabling said recording devices to record numbers while said adding wheels remain idle, and means 10 actuated by said connections to cause one of said numbers recording trains to print when a number is recorded, substantially as specified.
31. In an adding machine, a type-carrier, 20 a series of type carried by said type-carrier, a hammer operable to drive said type to print and movable to and from a retracted position, a pawl engaging and holding said hammer in its retracted position, a movable 25 actuator, a tripping element normally supported out of the path of movement of said actuator, means controlled by said type-carrier for moving said tripping element into the path of movement of said actuator, 30 an additional tripping element normally out of the path of movement of said actuator, and means for moving said additional tripping element into the path of movement of said actuator independently of said first- 35 named tripping element whereby said pawl may be released by said additional tripping element.
32. In an adding machine, a type-carrier, type supported by said type-carrier, a hammer operable to drive said type to print, a 40 pawl holding said hammer, a movable actuator, means controlled by said type-carrier and by said actuator for releasing said pawl from said hammer, and additional optionally operable means arranged to coöperate with said actuator to release said pawl from said hammer.
33. The combination with type-carriers, 45 numeral type on said type-carriers, a hammer for each type-carrier, latches for said hammers, means for operating said type-carriers to record numbers, means for releasing one of said hammers for each digit to be recorded, and adding mechanism, of a 50 key adjustable effectively to prevent said adding mechanism from operating, and means controlled by said key for causing one of said hammers to operate, substantially as specified.
60. 34. An adding and recording machine comprising a platen arranged to hold paper, a series of type-carriers, a series of numeral type on each type-carrier, hammers, springs for driving said hammers against said type, 65 hooks holding said hammers, a release de-
- vice connected to each of said hooks whereby said hooks will be automatically released when the corresponding type-carriers are operated, a special release device for one of said hooks, and a key for positioning said 70 special release device whereby the pawl will be released from the corresponding hammer at the will of the operator, substantially as specified.
35. In an adding machine, the combination of a series of type, a hammer for driving said type to print, a pawl holding said hammer, a bar connected to said pawl, means for engaging said bar to release said pawl to enable said hammer to operate, a special element for releasing said pawl, and a key for operating said special element, substantially as specified.
36. In an adding machine, the combination with the type-driving hammers, latches holding said hammers, a trip-bar for each latch and a plate connected to one of said latch bars, of a key, and connections whereby said key may set said plate in operative position, to act as a trip-bar, substantially as 80 specified.
37. In an adding machine, numbers recording mechanism including a type-carrier, means for operating said type-carrier to record numbers and another symbol, means for causing said type-carrier to record a symbol incidentally to the recording of numbers by other parts of said recording mechanism, and an adding wheel controlled by said type-carrier only when numbers are recorded thereby. 90
38. In an adding machine, numbers recording mechanism including a type-carrier, a hammer, mechanism controlled by said type-carrier for causing said type-carrier and hammer to coöperate effectively to record numbers, and additional optionally operable mechanism for causing said type-carrier and said hammer to coöperate effectively to record an indicating character other than numbers, incidentally to the recording of a number. 100
39. In an adding machine, numbers recording mechanism including a type-carrier, an adding wheel, means for operating said type-carrier effectively to record any digit from 1 to 9, means for operating said adding wheel when said type-carrier operates to record digits, means for causing said type-carrier to record an indicating character other than digits incidentally to the recording of a number, and means for holding said adding wheel idle during the operation of recording said indicating character. 115
40. In an adding machine, the combination with hammers arranged in numerical orders, a series of numeral type, means for coöperatively operating said hammers and type to print numbers, and adding mechanism to add the numbers printed, of a key 120
- 125
- 130

adjustable to prevent operation of said adding mechanism, and means for releasing one of the aforesaid hammers in addition to those required for printing certain numbers 5 when said key is adjusted as aforesaid, substantially as specified.

41. The combination with adding mechanism, series of type arranged in numerical orders, and hammers also arranged in numerical orders and operable to drive said type to print numbers, of mechanism adjustable to prevent operation of said adding mechanism when numbers are printed, and means controlled by said mechanism for releasing one of said hammers, substantially as specified.

42. The combination with type-carriers, numeral type on said type-carriers, mechanism for operating said type-carriers, to 20 position any desired type thereon in line for printing, a hammer for each of said type-carriers, and means for operating each of said hammers when the corresponding type-carrier is in one of several positions, of adding mechanism operable to add the numbers printed, a key, and connections controlled by said key to prevent said adding mechanism from operating and to cause one of the aforesaid hammers to be operated when a 25 number is printed, substantially as specified.

43. The combination with type-carriers, numeral type on said carriers, a hammer for each type-carrier, latches holding said hammers in idle position, means for operating 30 said type-carriers to record numbers, means for releasing one of said hammers for each numerical order in the number to be recorded, and adding mechanism for adding the numbers recorded, of a key, a link actuated by said key, means operated by said link to prevent said adding mechanism from operating when a number is recorded, and means actuated by said link to cause one of said hammers to be released when a number 35 is recorded, substantially as specified.

44. The combination with type-carriers, numeral type on said type-carriers, a hammer for each type-carrier, springs for actuating said hammers, latches holding said 40 hammers in idle position in opposition to said springs, means for operating said type-carriers to record numbers, means for releasing one of said hammers for each numerical order in the number to be recorded, adding 45 mechanism, and means for operating said adding mechanism incidentally to the recording of a number, of a key, a rocking element controlled by said key, means operated by said rocking element to prevent 50 operation of said adding mechanism when a number is recorded, and means operated by said rocking element to cause one of said hammers to be released, substantially as 55 specified.

45. The combination with adding mecha-

nism, series of type arranged in numerical orders, hammers arranged in numerical orders, latches holding said hammers, and means for operating said hammers to drive said type to print numbers, of a key, connections adjustable by said key to prevent operation of said adding mechanism when numbers are printed, and connections controlled by said key to enable a certain one of said hammers to operate when any other 70 of said hammers are operated, substantially as specified.

46. In an adding and recording machine, printing hammers, pawls for holding said hammers, a trip bar for releasing each pawl 80 from the corresponding hammer, and separate means for releasing one of said pawls.

47. In an adding machine, the combination with a printing hammer, a pawl arranged to engage with and hold said hammer, a swinging bail, means for operating said bail, a tripping element for releasing said pawl from said hammer, means for operating said tripping element into the path of movement of said bail to release said 90 pawl from said hammer, and means movable into the path of said bail independently of said tripping element whereby said bail will also release said pawl from said hammer.

48. In an adding machine, the combination with a printing hammer, and a latch device for said hammer, of plural means for releasing said latch device, substantially as described.

49. In an adding machine, the combination with a printing hammer, and a latch device holding said hammer, of means adjustable automatically under certain conditions for releasing said latch device from said hammer, and manipulative means adjustable independently of said automatic means for releasing said hammer.

50. In an adding machine, the combination with a type carrier, type carried by said type carrier, a hammer for driving said type to record, means for operating said hammer, a latch device for holding said hammer away from said type, automatic means for releasing said latch device incidentally to the positioning of certain of said 115 type for recording, and manipulative means controlling the release of said hammer independently of said automatic means.

51. In an adding machine, the combination with a printing hammer, and a latch 120 device holding said hammer, of plural means for releasing said hammer.

52. In an adding machine, hammers arranged in numerical orders, springs for actuating said hammers, pawls holding said hammers in position to retain said springs under tension, couplings whereby the release of a hammer in a higher order will release the hammers in lower orders, and optionally operable means for releasing a hammer in 125 130

one of the higher orders independently of the corresponding coupling, whereby the hammer so released will operate independently of the hammers in lower orders.

53. In an adding machine, hammers arranged in numerical orders, pawls holding said hammers, automatic means for releasing said pawls, and an additional manually operable device controlling the release of one of said pawls.

54. In an adding machine, the combination with hammers arranged in numerical orders, pawls holding said hammers, a series of settable elements, movable parts controlled by said settable elements, and means

under control of said movable parts for releasing said hammers as an incident to the operation of said parts into and out of engagement with said elements, of optionally operable means for releasing one of said hammers independently of the corresponding movable part aforesaid. 20

In testimony whereof, I hereunto affix my signature to this specification this 16th day of April, 1907, in the presence of two wit- 25

nesses.

SAMUEL G. DORMAN. [L.S.]
